UNITED STATES PATENT OFFICE.

HENRY W. GAYS, OF ST. LOUIS, MISSOURI.

CARLINE.

SPECIFICATION forming part of Letters Patent No. 651,138, dated June 5, 1900.

Application filed January 23, 1899. Serial No. 703,124. (No model.)

To all whom it may concern:

Be it known that I, HENRY W. GAYS, a citizen of the United States, residing at the city of St. Louis, State of Missouri, have invented 5 a certain new and useful Improvement in Carlines, of which the following is a full, clear, and exact description, such as will enable others skilled in the art to which it appertains to make and use the same, reference being had 10 to the accompanying drawings, forming part of this specification, in which—

Figure 1 is a cross-sectional view of a car-roof, showing my improved carline in position thereunder. Fig. 2 is a top plan view of 15 said carline, showing the side plates, purlins, and ridge-pole in dotted lines. Fig. 3 is a detail view of one end of said carline, part of the same being broken away. Fig. 4 is a detail view of one end of the carline, showing 20 a modification in which the horizontal member is used as a securing member. Fig. 5 is a detail view of one end of the carline, in which the vertical and horizontal members each act as securing members. Fig. 6 is a 25 sectional view of one side of the car-roof, showing the modification shown in Fig. 5 in position, wherein the horizontal member is bent upwardly and over the side plate. Fig. 7 is a similar view where said horizontal member is extended downwardly on the outside of 30 the side plate. Fig. 8 is a detail view of one end of the carline, in which the horizontal member is flush with the side plate and bent downwardly on the outside thereof. Fig. 9 is an end 35 view of a T-shaped carline, in which the horizontal member is bent downwardly to form a securing member. Fig. 10 is a side elevational view from one end of the carline illustrated in Fig. 9. Fig. 11 is a top plan view of the 40 same. Fig. 12 is an end elevational view of a T-shaped carline, in which the vertical member is bent laterally for the purpose of securing the carline in position. Fig. 13 is a side elevational view of one end of the same, and 45 Fig. 14 is a top plan view of one end of said carline.

This invention relates to a new and useful improvement in metallic carlines for use in car construction, the object being to dispense 50 with hangers and pockets which afford attaching means for the carline and the purlins.

and ridge-pole thereto, the carline itself being so formed as to provide said attaching means. By so constructing a carline I am enabled to make the same from commercial 55 forms, such as commercially-rolled iron or steel, the ends of which are cut and bent to form the attaching or securing means to the side plates, the horizontal webs of the carline being notched or scored and struck up to 60 form lateral buttresses or pockets to receive the purlins and ridge-pole.

With these objects in view my invention consists in cambering a commercially-rolled iron or steel bar, cutting and bending its ends 65 to form attaching devices to the side plates, and providing the same with pockets for the reception of the purlins and ridge-pole.

Other features of the invention reside in the construction, arrangement, and combination 70 of the several parts, all as will hereinafter be described and afterward pointed out in the claims.

In the drawings, A indicates the side plates, B the purlins, C the ridge-pole, and D the under-roof sheathing, and E the outer-roof sheathing, of a car, such parts being of the 75 usual well-known construction.

F indicates my improved carline, which, as shown in Figs. 1 to 8, is of inverted-L shape 80 in cross-section and suitably cambered to conform to the pitch of the roof. This carline, as shown in Figs. 1, 2, and 3, has its horizontal web or member preferably notched or scored, as at f, and struck up to form lugs or 85 buttresses f' at such points or places as will properly position the purlins and ridge-pole between each pair of lugs on the carline. These lugs prevent lateral movement of such parts, and in order to secure said purlins and 90 ridge-pole in position I employ bolts b and c, respectively, which pass therethrough and through suitable openings in the horizontal member of the carline. In order to secure the ends of the carline to the side plates, I 95 utilize a bent extension of either the vertical or the horizontal members, which bent extensions are perforated to receive bolts or lag-screws, as is well understood. As shown in Fig. 3, the horizontal member of the carline 100 is cut short and the vertical member bent at right angles under the horizontal member,

said bent portion being provided with two bolt-openings for the reception of bolts or lag-screws, by which the carline is attached to the side plates. This form of attaching medium I have marked F' in the drawings, which form is also shown in Figs. 1 and 2. In Fig. 4 the vertical member is cut short and the projecting end of the horizontal member bent downwardly and formed with bolt-openings to afford an attaching medium of the carline to the side plate. This bent extension I have marked F^2 in the drawings. The object of making these bent extensions in the same plane as the inner face of the side plate is to provide a large surface area for abutment against the side plate to prevent wearing away of said side plate by "chafing," due to the movement of the parts of the car under strain, twists, &c. In Fig. 5 I have shown the vertical member bent at right angles to form the attaching-plate F' , similar to that shown in Figs. 1, 2, and 3, and instead of cutting the horizontal member short, so that it can abut against the inner face of the side plate, said horizontal member is extended over the upper face of the side plate, as shown at F^3 , and formed with a bolt-opening for the passage of a lag-screw or bolt to provide an additional attaching medium. The object in this extension F^3 is to provide a secure means of attachment of the carline to the side plates to prevent the side plates from spreading under strain and also to relieve the bolts which secure the bent portion F' in place from longitudinal strain, which would tend to loosen the nuts on the same and strip said bolts of their threads. The form shown in Fig. 5 contemplates the carline being arranged in such position as to be flush or a little above the upper faces of the side plates. In Fig. 6 I have shown a construction wherein the carline may be positioned below the upper faces of the side plates and at the same time get the advantage of the extension F^3 , which can be done by bending said extension upwardly and outwardly, as clearly shown in Fig. 6. In Fig. 7 I have shown the extension F^3 as being provided with a portion F^4 , bent downwardly at substantially right angles to engage the outer face of the side plate. This extension F^4 in this construction is provided with a bolt-opening in line with one of the bolt-openings of the bent portion F' for the purpose of clamping said members against the side face of the side plate. This member F^4 offers additional security in preventing the lateral spreading of the side plates, and by the presence of the cross-piece above the side plate the carline is firmly supported in position. As shown in Fig. 8, the carline is designed to be flush or slightly above the upper face of the side plate, while in Fig. 7 I have shown a construction of a carline designed to be located below the upper face of the side plate, in which the horizontal member is bent upwardly, affording an increased area for the end abutment of the carline

against the side plate, said upward extension being then bent outwardly and downwardly, corresponding in this latter respect to the construction shown in Fig. 8.

In Figs. 9, 10, and 11 I have shown a **T** form of carline in which the vertical web is cut off short and the horizontal member is bent downwardly, as at F^5 , for the purpose of affording an attaching means to the side plate, said bent portion being provided with bolt-holes for obvious purposes.

In Figs. 12, 13, and 14 I have shown a **T** form in which the horizontal member is cut off short and the vertical member bent laterally and provided with bolt-holes for attachment to the side plate in substantially the same manner as shown in Fig. 3, heretofore described.

While I have shown **L** and **T** shaped commercially-rolled forms to illustrate the manner in which my invention can be carried out, still it is obvious that there are other commercially-rolled forms which can be used in substantially the same manner, and, furthermore, that while I have illustrated the simplest means of providing attaching devices for securing the carline to the side plates, yet I do not wish to be understood as being limited to the exact manner of bending the several members of my carline as shown in the drawings, as I am aware that other cuts and bends can be made without in the least departing from the nature and principle of my invention.

Having thus described my invention, what I claim, and desire to secure by Letters Patent of the United States, is—

1. A carline comprising a commercially-rolled form, having suitable horizontal and vertical members integral with each other, said vertical member at each end being bent at right angles, said bent portions at each end being formed with bolt-openings, and said horizontal portions at each end of the carline being extended across and then bent downwardly, said last-named or downwardly-extending portions being formed with bolt-openings, substantially as described.

2. The combination with a carline comprising a metal bar suitably cambered and having horizontal and vertical members integral with each other, the horizontal member having lugs or projections struck up therefrom in pairs and provided with a hole in the horizontal portion between the lugs of each pair, of purlins held between said lugs and secured by securing devices passed through the holes in the horizontal portion.

3. A carline comprising a horizontal member, and a vertical member integral therewith, suitably cambered to conform to the pitch of the car-roof, said horizontal member being scored and struck up to form pockets for the reception of purlins and ridge-pole, the ends of said carline being cut and bent to afford securing means to the side plates; substantially as described.

4. A carline comprising a commercially-
rolled form bent longitudinally at or near the
center to form an integral, horizontal and
vertical member and cambered throughout
5 its length, the horizontal portion having lugs
or buttresses struck up therefrom in sets and
provided with a bolt-hole between said sets
of lugs or buttresses, and the extreme ends
of the carline bent laterally and perforated

to receive a bolt or other securing means for fastening the carline in place.

In testimony whereof I hereunto affix my
signature, in the presence of two witnesses,
this 12th day of January, 1899.

HENRY W. GAYS.
